UNITED STATES PATENT OFFICE

JOHN C. ROGERS, OF CICERO, ILLINOIS, ASSIGNOR TO CROWN STOVE WORKS, OF CICERO, ILLINOIS, A CORPORATION OF ILLINOIS

DESIGN FOR A SUPPORTING BRACKET FOR DOOR AND DRAWER HANDLES

Application filed May 18, 1931. Serial No. 39,886. Term of patent 7 years.

To all whom it may concern:

Be it known that I, JOHN C. ROGERS, a citizen of the United States, residing at Cicero, in the county of Cook and State of Illinois, have invented a new, original, and ornamental Design for a Supporting Bracket for Door and Drawer Handles, of which the following is an specification, reference being had to the accompanying drawings, forming part thereof.

Figure 1 is a front elevation of a support-

ing bracket for door and drawer handles, showing my new design, and

Figure 2 is a side elevation thereof.

I claim:

The ornamental design for a supporting bracket for door and drawer handles, as shown.

JOHN C. ROGERS.
